UNITED STATES PATENT OFFICE.

OTIS KARL LINSCHOTT, OF TEKOA, WASHINGTON.

POCKET CHECK-PROTECTOR.

1,398,235.

Specification of Letters Patent. Patented Nov. 29, 1921.

Application filed June 27, 1921. Serial No. 480,646.

To all whom it may concern:

Be it known that I, OTIS KARL LINSCHOTT, a citizen of the United States, and resident of Tekoa, county of Whitman, State of Washington, have invented a new and useful Pocket Check-Protector, of which the following is a specification.

The present invention relates in general to devices for preventing fraudulent alteration 10 in negotiable paper such as bank checks, drafts, and the like, and has reference more particularly to a small and compact device of this character which may be conveniently carried upon the person so that it may be 15 handy for use at all times.

A further feature of the invention resides in the simplicity of construction which will enable the device to be made and sold at an exceedingly modest cost without sacrificing 20 the efficiency of the same.

With these and other objects in view, the invention will now be described with reference to the accompanying drawing, in which Figure 1 is a perspective view of a 25 device made in accordance with the preferred embodiment of the invention, Fig. 2 is a perspective view of the device as folded, Fig. 3 is a detail cross section illustrating the use of the device, Fig. 4 is a detail view 30 in longitudinal section showing the coöperative position of the printing characters with the inking pad, and Fig. 5 is a detail view of a portion of a check after it has been protected by the device.

35 Referring now to the drawings in detail, (1) and (2) represent a pair of plates hinged at one end as at (3), the plate (1) representing the top and the plate (2) representing the bottom. Arranged on the inside face of 40 the plate (1) are a series of printing characters (4) which stand out in relief and act in the capacity of type. These characters are arranged in series to indicate a maximum amount so that any one of the series may be 45 utilized for printing on a check or other negotiable paper the maximum amount for which the check is made out for.

The bottom plate (2) is made with channel side edges (5) and (6) with an open front 50 end (7) and a ledge (8) at the back end. Arranged transversely of the plate (2), with its ends confined in the channels (5) and (6), is an inking pad (9), the bottom side of which carries a pointer (10) which protrudes through an elongated opening (11) in the plate and with indicating characters

(12) along the outside margin of the plate adapted to coöperate with the pointer (10) to indicate a selective positioning of the inking pad (9) relative to the printing characters (4) so that any one of the series of printing characters (4) may be utilized to print the check when the same is presented between the plates and the plate (1) has been folded over the plate (2). 60

To hold a sliding adjustment of the inking pad (9) on the plate (2), a multiplicity of small studs (13) are arranged longitudinally of the slot (11) and with which the under side of the inking pad frictionally engages. 70 A like multiplicity of these studs (14) are also arranged on the outside of the plate (2) to co-act with the pointer (10) as an extra precaution to prevent the inking pad (9) from slipping out of alinement with the selected one of the series of printing characters (4). 75

The side edges of the plate (1) are arranged with downwardly presented flanges (15) which leaves the front end (16) open 80 the same as the front end (7) of the plate (2). Thus when the plates are folded the front end of the device is open so that the end of the check may extend from the device as best shown in Fig. 2. 85

In using the protector the plates (1) and (2) may be opened and after the inking pad (9) has been moved to its proper position in alinement with that one of the series of printing characters which are to be used, the 90 check may be presented in the plates so that pressure exerted preferably around that area of the plates adjacent the position of the inking pad will act to print that one of the series of printing characters selected. The 95 printing will occur on the check preferably along one edge, as best shown in Figure 5, in which the check is represented by the numeral (17).

It is of course understood that the printing characters (4) may be of any desired structure, such, for instance, as a customary perforating type, if desired. It is to be also understood that various changes may be made in the detail construction of the device 105 without departing from the spirit of the invention as recited in the subjoined claims.

I claim:

1. A pocket check protector comprising a pair of plates, the inner face of one plate having a series of fixed printing characters and the other plate having a movable inking de- 110

- vice adapted to selectively coöperate with said series of printing characters to selectively reproduce any one of said series of characters on a check when presented between said 5 plates.
2. A pocket check protector comprising a pair of hinged plates, the inner face of one plate having a series of printing characters, and the other plate having a slidably carried 10 inking pad adapted to be moved to selectively coöperate with said series of printing characters to selectively reproduce any one of said series of characters on a check when presented between said plates, the outer 15 face of the plate carrying the inking pad having a series of indicating characters corresponding to the said series of printing characters, and a pointer mounted to the under side of the inking pad and protruding 20 through an elongated slot in the plate which carries the inking pad adapted to coöperate with the indicating characters to selectively position the inking pad relatively to any one of said 25 series of printing characters.
3. A pocket check protector comprising a pair of hinged plates, the inner face of one plate having a series of printing characters, and the other plate having a slidably carried 30 inking pad adapted to be moved to selectively coöperate with said series of printing characters to selectively reproduce any one of said series of characters on a check when presented between the said plates, the outer face of the plate carrying 35 the inking pad having a series of indicating characters corresponding to the said series of printing characters, and a pointer mounted to the under side of the inking pad and protruding through an elongated slot in the plate which carries the inking pad adapted to coöperate with the indicating characters to selectively position the inking pad relatively to any one of said 40 series of printing characters, and friction means for holding the inking pad in alinement with any one of said series of printing characters.
4. A pocket check protector comprising a pair of hinged plates, the inner face of one plate having a series of printing characters, and the other plate having a slidably carried 45 inking pad adapted to be moved to selectively coöperate with said series of printing characters to selectively reproduce
- any one of said series of characters on a check when presented between said plates, the plate which carries the inking pad having channelled side edges with the ends of the inking pad confined in said channels. 55
5. A pocket check protector comprising a pair of hinged plates, the inner face of one 60 plate having a series of printing characters, and the other plate having a slidably carried inking pad adapted to be moved to selectively coöperate with said series of printing characters to selectively reproduce any one of said series of characters on a check when presented between said plates, the outer face of the plate carrying the inking pad having a series of indicating characters corresponding to the said series of printing characters, 65 and a pointer mounted to the under side of the inking pad and protruding through an elongated slot in the plate which carries the inking pad adapted to coöperate with the indicating characters to selectively position the inking pad relatively to any one of said series of printing characters, the plate which carries the inking pad having channelled side edges with the ends of the inking pad 70 confined in said channels. 75
6. A pocket check protector comprising a pair of hinged plates, the inner face of one plate having a series of printing characters, and the other plate having a slidably carried 80 inking pad adapted to be moved to selectively coöperate with said series of printing characters to selectively reproduce any one of said series of characters on a check when presented between the said plates, the outer face of the plate carrying the inking pad having a series of indicating characters corresponding to the said series of printing characters, and a pointer mounted to the under side of the inking pad and protruding through an elongated slot in the plate which carries the inking pad adapted to coöperate with the indicating characters to selectively position the inking pad relatively to any one of said series of printing characters, and friction means for holding the inking pad in alinement with any one of said series of printing characters, and channelled side edges with the ends of the inking pad confined in said channels. 85
- 100

OTIS KARL LINSCOTT.
